(57) CLAIM

The ornamental design for an iron golf club head, as shown and described.

DESCRIPTION

FIG. 1 is a toe, back perspective view of our new iron golf club head;

FIG. 2 is a top view thereof;

FIG. 3 is a heel side view thereof;

FIG. 4 is a back view thereof;

FIG. 5 is a toe side view thereof;

FIG. 6 is a front view thereof; and,

FIG. 7 is a bottom view thereof.

The portion of the club head shown in phantom is for illustrative purposes only and does not form any portion of the claimed design.
